UTILITY CART

John P. Salsgiver, West Acton, Mass., assignor to United Technical Corporation, West Concord, Mass.

Filed June 6, 1969, Ser. No. 17,558

Term of patent 14 years

Int. Cl. D12—02

U.S. Cl. D14—3

Fig. 1.

Fig. 2.

Fig. 3.

FIG. 1 is a plan view of the utility cart showing my new design;

FIG. 2 is a view in side elevation of the utility cart; and

FIG. 3 is a view in end elevation of the utility cart. The rear is flat and plain, and the right side and depending shelf are both flat and plain.

I claim:

The ornamental design for a utility cart, as shown and described.
